US00D613538S

(12) United States Design Patent
Cattacin et al.

(10) Patent No.: US D613,538 S
(45) Date of Patent: * Apr. 13, 2010

(54) PAPER DISPENSER

(75) Inventors: Gilles Cattacin, Colmar (FR); Yoann Denis, Colmar (FR); Nicolas Pommier, Colmar (FR)

(73) Assignee: Georgia-Pacific France (FR)

() Term: 14 Years

(21) Appl. No.: 29/314,461

(22) Filed: Apr. 2, 2009

(30) Foreign Application Priority Data

Oct. 8, 2008 (EM) 001017545

(51) LOC (9) Cl. 23-02

(52) U.S. Cl. D6/523

(58) Field of Classification Search D6/518-523; 242/570, 590, 598; 312/34.1; 206/389; 211/85.5
See application file for complete search history.
